PITCHING GAME TARGET

Thirl W. Waddle, Fort Worth, and Jackie D. Wood and Verner L. Jackson, Weatherford, Tex.; said Wood and said Jackson assignors to J. Lloyd Patton, Fort Worth, Tex.

Filed Dec. 18, 1970, Ser. No. 26,565

Term of patent 14 years

Int. Cl. D21—01

U.S. Cl. D34—5

FIG. 1

FIG. 2

FIG. 3

FIG. 4

FIG. 1 is a front perspective view of a pitching game target showing our new design;

FIG. 2 is a front elevation view of a pitching game target showing our new design;

FIG. 3 is a side view of a pitching game target showing our new design; and

FIG. 4 is a top view of a pitching game target showing our new design.

The back of the pitching game target showing our new design is unornamented and is shaped as shown in FIG. 2.

We claim:

The ornamental design for a pitching game target, as shown and described.
